TYPEWRITING MACHINE

Jesse A. B. Smith, Stamford, Conn., assignor to
 Underwood Elliott Fisher Company, New York,
 N. Y., a corporation of Delaware

Application November 15, 1935, Serial No. 49,863

24 Claims. (Cl. 197—63)

This invention relates to typewriting machines, and particularly to improvements in the manner of establishing uniform side margins and uniform positions of generally recurring indentations, such as date lines, paragraphs and signature lines.

The invention provides novel, easily operated means whereby the operator may select a writing line-length which will centrally locate the correspondence on the stationery, and thus produce work of pleasing appearance, and automatically coacting means which will establish definite positions, best suited to the writing line-length selected, for the indentations referred to.

One feature of the invention combines tabulating means, in which the stops, when established for tabulating purposes, do not conflict with, or necessitate a readjustment of, the stops used for correspondence indentations, making it possible to write tabulated or statistical matter on a machine generally used for correspondence.

This improvement is comparatively simple and is readily adjustable. The operator is enabled to change from a long writing line to a short one by the simple expedient of turning a knob, and to locate the intermediate indented portions of a letter uniformly, by merely pressing a tabulator-key. The positions of the various sections of the letter are thus uniformly maintained without special effort or skill on the part of the operator, resulting in improved work and saving in time.

Experience has indicated that for general correspondence, a selection of three writing line-lengths will be sufficient, and that fixed indentations may be established to suit the writing line-lengths.

This improvement includes two control racks, which are rotatably mounted on the carriage of a typewriting machine and so linked to each other that the rotation of one of the racks will rotate the other. The cross-section of these racks may be square, so as to provide four operative positions, or there may be other suitable cross-section. On both of these racks, letter-spaced notches are cut on all four surfaces, over the entire effective length. On the upper or margin rack, four pairs of margin-stops may be adjustably attached to establish the various line-lengths and corresponding margin-widths required. The lower or tabulating rack is preferably connected by a chain belt to the margin-rack. For each set of margin-stops on the margin-rack, a corresponding set of two or more stops may be provided on the tabulating rack. The relation between the respective sets of tabulating rack and

margin-rack stops being kept constant by the synchronizing means, uniform positions of the indented portions of the typewriting, regardless of the line-length used, are automatically established. One or more of the sets of stops on the margin-rack and the corresponding sets of stops on the tabulating rack may be used to co-operate in tabulating, in order to provide the number of columns or tabular positions required for the class of work to be performed.

A counter-stop may be provided to successively engage one pair of margin-stops in the conventional manner. The stops on the lower or tabulator rack may be engaged by a set of tabulator counter-stops, each of which is actuated by a separate tabulator-key, or two or more of the tabulator-stops may be actuated by one tabulator-key and counter-stop.

A change to a short or longer line-length may thus be effected by rotating the margin-shaft with its corresponding stops to one of the other operative positions, bringing a selected set of margin-stops and the corresponding set of tabulator-stops into their operative positions.

Regardless of the line-length utilized by the operator or of the changes in line-length made in the course of typewriting, the conventional line-end signal and the line-end-key lock continue to function in the normal manner.

The line-end margin counter-stop preferably actuates the conventional type of line-end-key lock, as well as the conventional type of line-end signal, by means of a suitable mechanism which may be provided.

Other features and advantages will herein-after appear.

In the accompanying drawings,

Figure 1 is a fragmentary, perspective view of the typewriting machine, showing the margin and tabulator racks and the interconnecting means, and the coordination of the line-end-signal device, key-lock and tabulator-keys.

Figure 2 is a perspective of one of the margin-rack stops.

Figure 3 represents a typical typewritten letter, in diagrammatic form, showing an intermediate line-length.

Figure 4 is a side elevation form of tabulator-rack stop in position in the rack.

Figure 5 is a side elevation of another form of tabulator-rack stop in position in the rack.

Figure 6 is an elevation of the right-hand carriage-end plate.

Figure 7 is an elevation, partially in section, of the machine of Figure 1.

Figure 8 is a fragmentary plan view showing a work-sheet in position, and the stops set for a short line-length.

Figure 9 is a view similar to Figure 8, showing tabulator work in progress.

Figure 10 is a diagrammatic representation of a letter, showing a long line-length.

Figure 11 illustrates the camming action of the margin-stop heads, in passing the margin-10 counter-stop.

Figure 12 illustrates the margin-counter-stop in inoperative position.

The detailed arrangement of the invention, as incorporated in a typewriter of the noiseless class, 15 may be as follows:

Two racks 25 and 26, Figure 1, of square or other suitable cross-section are each rotatably mounted, preferably on the carriage ends 27 and 28 of a laterally slideable carriage 30 behind a reversible platen 31 of a typewriting machine. Letter-spaced notches 32 are cut over the effective length of the racks 25, 26 on all four surfaces thereof.

A sprocket-wheel 33, with an attached control 25 knob 34 for manual rotation, is preferably attached to one end of the upper or margin rack 25, and a similar sprocket-wheel 35, having the same number of teeth, is attached to the lower or tabulating rack 26. A chain 36, or suitable gearing, 30 may be utilized to drive the lower sprocket 35 from the upper sprocket 33, thus synchronizing the two racks. Four sets of pronged margin-stops 37, 38, 39 and 40 are preferably slidably fitted into the notches 32 of the margin-rack 25, 35 with the heads 41 of each set of stops disposed in a separate quadrant. The left and right stops of a set 40, for example, respectively determine the left and right ends of a predetermined shortest writing line length. Each stop of a set may be located equidistantly from the center of the machine or at varying distances from the center; and each succeeding set may be increasingly separated so that the four sets provide four selections of writing line-length, and corresponding margin-widths under the control of the operator.

The heads 41 of the marginal rack-stops 37 to 40, inclusive, are inclined, as indicated in Figure 2, to provide a camming surface for a purpose later described. The prongs 42 of the stops closely engage the sides and roots of the notches 32. A 50 spring detent 43, having a peak 44 arranged to engage a corner of the notch into which the stop may be fitted, as shown in Figure 5, may be attached to the head 41 for yieldably locking the stop in position in rack 25.

Additional sets of stops 45, 46 and 47, each set consisting of one or more individual stops, may be adjustably fitted on three faces of the tabular rack 26 to co-operate with stops 38, 39, 40 of the marginal rack 25, to establish the customary letter indentations, such as paragraph, date line and signature line. The fourth or bottom sides of racks 25 and 26, as shown in Figure 1, have stops arranged for statistical or tabular work; the margin-stops 37 on rack 25 providing the greatest line-width, and the tabulating stops, designated by symbols 48^a, 48^b, 48^c, 48^d, etc., of any required number, gaging the various column positions.

The stops 45 to 48, inclusive, are similar in design to the margin-rack stops 37 to 40, inclusive, with the exception that the heads 41 are not inclined, as shown in Figure 5.

When two or more stops on different surfaces of rack 26 are to have the heads 41 in the same lateral position with respect to the center of the

machine, a multiple stop 49, Figure 4, having two or more heads located at right angles to each other, may be utilized. The spring detent 43 may be used with this stop also, to retain said stop on the rack 26.

The operator establishes the various writing line-lengths desired, so as, for example, to centrally locate short, medium and long-line letters on standard size stationery, by locating the marginal stops 37 to 40 in rack 25 with relation to the usual side-gage 50 on paper-table 50^a, Figure 7, and the usual line-scale 50^b. The margin-stops for the left-hand margin are placed with their heads 41 inclining to the right; those for the right-hand margin having their heads inclining leftwardly.

The indentations for date line, paragraph and signature lines are similarly established by positioning the stops on rack 26. The margin and the indenting or tabulating stop positions, once having been established, may be left undisturbed for practically all types of correspondence.

When a line-length is to be changed, the stationery 29, Figure 8, having previously been introduced around the platen 31 in the usual manner, 25 knob 34 is rotated by the operator until the desired set of stops, as 40, is brought into operative position, that is, with the heads 41 facing rearwardly. For convenience, a symbol 51, identifying the stops in their operative positions, may be 30 located on the circumference of the knob 34.

The line-length-changing rotation of the shaft 25 causes a simultaneous rotation of shaft 26, and thus brings such stops 45, 46, or 47, into operative position as are appropriate for the indentations, 35 such as paragraph, date and salutation lines, for the new line-length.

A spring-detent 52, or other suitable locking mechanism, fastened preferably to the left carriage-end 27 and having an extended spring-arm 40 53, is preferably held in engagement with one of the faces of the margin-rack 25, thus retaining the rack and the corresponding set of margin and tabulator stops in the selected operative positions.

A margin-counter-stop 54, is usually located at 45 the center of the machine, between the stop-faces of the operative margin-stops, as 40, in Figure 1, to control the lateral movement of the carriage in both directions.

The detailed arrangement of the margin counter-stop and the controls therefor as later described herein may be substantially as used on the Underwood Noiseless typewriter.

When the line-length has been established, the carriage is moved to the right until the edge 41^a 55 of the left margin-stop 40, Figure 8, engages the contact face 55 of the counter-stop 54. The typewriting proceeds in the usual manner with the carriage moving in the letter-feeding direction until the end of the line is reached, when the face 55 of the counter-stop 54 engages the corresponding right margin-stop 40, limiting the line-length and the margin-width.

When a deeply indented line, i. e., R, Figure 8, is to be typed, the operator repeatedly depresses 65 a tabulator-key 57 which is operatively connected to a tabulator counter-stop 58 located near the center of the machine. A spring-motor 56, Figure 7, draws the carriage leftwardly, in the usual manner, the carriage having been freed 70 of its normal, letter-space movement as later described, until the head 41 of the right-hand stop 47 engages the tabulator-stop 58, the top of which is brought forward by depressing the tabulator-key 57, thus arresting the movement 75

of the carriage. The typewriting is begun at this point, and proceeds until the edge 41^a of the right margin-stop 40 engages the margin counter-stop 54, thus determining the right line-end. 5 When a paragraph-indentation is reached, as indicated in Figure 8, the operator depresses the tabulator-key 57 until the carriage in its leftward movement brings the left-hand stop 47 into engagement with the tabulator counter-stop 58. 10 When an intermediate indentation, i. e., tabulation P, Figure 8, is reached, the tabulator-key 57 is repeatedly depressed until the appropriate intermediate stop engages the tabulator counter-stop 58. The number of line-indenting stops provided at each operative position of shaft 26 depends upon the number of recurring indentations encountered in the class of work to be performed and may be varied. 15

When a longer line-length, as in Figure 10, is desired, the operator rotates the knob 34 until the selected set of margin-stops, i. e., 38 on the margin-shaft 25 and the corresponding line-indenting stops, as 45 on the tabulator-shaft 26, are in the operative position. 20 For any indentation or line-start that may be the same for each line-length, as the signature-line of each letter, the multiple-faced stop 49 may, if desired, be common to three positions of the line-indenting or tabulator-rack 26. Said multiple stop 49, as indicated in Figure 4, has three heads 41 respectively perpendicular to the corresponding faces of the tabulator-shaft. 25

One of the sets of margin-stops, as 37, and the corresponding set of tabulator-stops 48^a, 48^b, 48^c, etc., may be arranged to co-operate with the usual denominational tabular keys 57, 59, 60, 62, 64, on the machine keyboard for tabulating or statistical work, a sample of which is indicated in Figure 9. The knob 34 is rotated until the identification symbol 51 indicates that the stops 37 on the margin-shaft and the corresponding tabulator-stops on the tabulator-shaft are in their operative positions. The left margin-stop 37 operates to establish the left margin in the manner previously described with reference to stop 40. When tabulation at column A, Figure 9, is desired, the appropriate tabulator-key, for instance 60, Figures 1 and 7, is depressed, bringing the top of a tabulator counter-stop 61 forwardly into the path of the tabulator-stop 48^a on tabulator-rack 26. The carriage travels leftwardly until it is arrested by the engagement of tabulator counter-stop 61 with tabulator-stop 48^a, as previously described, thus establishing the column 45 and the correct denominational position of the work. For column C, tabulator-key, say 62, is depressed, similarly bringing the operative end of counter-stop 63 forward into engagement with tabulator-stop 48^c. Other columns, as D, may 50 similarly be established by depressing the appropriate tabulator-key, to establish the column position on the work-sheet and the correct denominational position of the typing by the engagement of the associated counter-stop with one of the other 55 marginal stops 48^a, 48^b, 48^c, etc.

In the type-action fragmentarily indicated in Figures 1 and 7, when a character-key 66 is depressed, its associated key-lever 67 drives a type-carrier 68 through a linkage 69 toward the platen 31, mounted in the carriage 30. A letter-feed rack 71 on the carriage meshes with a pinion 72, coupled, as shown in Figure 7, by a shaft 73 to an escapement-wheel 74 at the bottom of the shaft, said wheel co-operating with a type-key-controllable dog-rocker 75 and the spring- 75

motor 56 to letter-feed the carriage, which is guided by the usual co-operating rails 70 and anti-friction elements 70^a.

As indicated in Figure 8, the tabulator-counter-stops such as 58, 61, etc., are normally clear of whatever tabulator-rack-stops are in their operative positions at the time. The operative end of any counter-stop, 61 for example, is brought forward into the path of the tabulator-rack-stops by means of a tabulator-key lever 77, 10 Figure 7, fulcrumed on a shaft 78 to the machine-frame 76. The means for projecting the tabulator-counter-stop 61 forwardly by the action of the tabulator-key 60, and the means for controlling the carriage movement may be substantially as used in the Underwood Noiseless typewriter, and may therefore be briefly described as follows:

When the tabulator-key 60 is depressed, the rear end 80 of the key-lever 77 raises the rounded base 81 of the tabulator-counter-stop 61, and, through the intermediary of the sloping guide-way 79 and a diagonally cut slot 82 in the counter-stop 61, which slidably engages a pin 83 fixedly mounted on the carriage-frame extension 84, 25 causes the counter-stop 61 to move forwardly, bringing the top of it into the path of any of the tabulator-rack-stops in operative position. A spring 85, connecting an arm 86 of the tabulator-counter-stop to a pin 87, fixedly mounted on the extension 84 of the carriage-frame, by means of a hook 88, returns the tabulator-counter-stop rearwardly to its original position, out of line with the tabulator-stops, when the tabulator-key is again released. 35

Depressing any one of the tabulator-keys releases the carriage-feed, and allows the spring-motor 56 to move the carriage leftwardly until one of the tabulator-stops in the operative position, as 48^a, engages the tabulator-counter-stop 40 moved into its operative position by said key. When the tabulator-counter-stop, as 61, is moved forwardly by the tabulator-key lever 77 as previously described, the arm 86 of the tabulator-counter-stop causes a cross-bar 91, Figure 1, 45 which is attached by arms 92 to a shaft 93 journaled in the frame 84, to rotate upwardly. An extension 94 attached to said cross-bar and pivotally connected, as at 95, to a lever 96, urges said lever downwardly, rotating a link 97, pivotally mounted at 98 to the frame, and articulated to the lever 96, forwardly. The front edge 99 of said link engages a finger 102 on a dog 100 pivotally mounted on the dog-rocker 75, Figure 1, 50 rotating said dog out of engagement with the teeth 103 of the escapement-wheel 74, permitting the carriage to move freely, a companion dog 101 being also out of engagement with wheel 74. 55

Upon releasing the tabulator-key 60, the tabulator-counter-stop returns to its original position. 60 A spring 104, attached to the rear end of the link 97, rotates the link rearwardly about its pivot 98, the releasing finger 102 on the dog 100 allowing a spring 105 to restore said dog into engagement with the teeth 103 of the escapement-wheel, thus arresting the movement of the carriage. 65

For each line-length established as described, by rotation of the margin-rack 25 to one of its operative positions, it is desirable that a line-end 70 signal be given as the carriage reaches a point the customary distance from the end of the line. To this end, there is employed a finger 106, the end of which is disposed in the path of the right margin-stop, as 40, for operating a line-end-sign- 75

nal device. The finger is a forwardly bent portion of a rod 107 which is swingably journaled in two brackets 108 and 109, as indicated in Figures 1 and 7, a collar 109^a supporting the rod on bracket 109. The bottom end of rod 107 terminates in a striker 110, which coacts with a bell 111 to sound the line-end signal. When the margin-stop 40 engages the finger 106, near the line-end, the rod 107 is leftwardly rotated through a small angle, a spring 112, attached to an extension of the rod 107, resisting said rotational movement. When the finger 106 is disengaged from the stop 40, the tension of the spring 112 causes the rod to sharply return to its normal position, the striker 110 sounding the bell 111.

In order that a line-end key-lock and key-release may function when the carriage has traversed the usual number of letter-spaces after the line-end-signal, as indicated in Figure 3, regardless of the line-length as determined by the margin-control mechanism, the margin-counter-stop 54, Figure 1, is preferably arranged to co-operate in the key-locking and key-releasing. When the right margin-stop 40 contacts the face 55 of the margin-counter-stop 54, it imparts a limited leftward displacement to the counter-stop which may be used for key-locking as indicated in Figure 1. Said displacement after it has taken place may be negatived to release the locked keys for the customary margin-release by moving the counter-stop 54 rearwardly until it is out of range of the margin-stop 40.

The margin-control mechanism may therefore be combined with known means as shown, whereby the displacement and escape of the counter-stop 54 effect respectively the key-locking and margin-release. The counter-stop 54 is supported by a vertical arm 113, the bottom of which terminates in a bracket 114, formed with a shelf 115 which is pivotally suspended, by means of a vertical pin 116, to a block 117, to which a shank 118 is attached. This vertical pivoting of the margin-counter-stop-support 113 enables the counter-stop 54 and its associated bracket 114 to be rotated leftwardly about pin 116, and the crosswise pivoting of the block 117, by means of the shank 118, journaled in the machine-framework 76, enables the upper end of the counter-stop 54 to be moved rearwardly.

In its leftward displacement, by means of stop 40, to a position indicated by the dotted line, Figure 1, the counter-stop 54, through the medium of an arm 126, attached to the bracket 114, and a link 127, draws a key-locking bail 128 rearwardly under locking shoulders 129 of the typing key-levers 67, thus locking the keys at the completion of a line as determined by the right margin-stop 40. This leftward displacement of the counter-stop 54 is against the pull of a spring 130, which normally retains the face 55 of the counter-stop against an abutment 131 afforded by the machine-framework 76.

Where it is desired to extend the writing-line beyond the limit established by the right-hand margin-stop 40, a margin-release key 120 on the keyboard is depressed, actuating key-lever 121 which is pivotally mounted on a pin 122, raising a yoke 123 at the opposite end of the lever. An arm 124 of the shank 118, slidably fitted in the 70 yoke 123, causes the block 117 to turn clockwise of Figure 7, about the shank 118, thus, by swinging the arm 113 rearwardly, carrying the counter-stop 54 back, out of engagement with the margin-stop 40, as indicated by the dotted lines, Figures 7 and 12.

Upon the escape of the counter-stop 54 from the margin-stop 40, the key-locking bail 128 moves forwardly to release the key-levers 67, since, by the tension of spring 130, the bracket 114 will move about pin 116 so as to rotate the arm 126 forwardly.

Upon the release of the key 120, a spring 125 raises the lever 121 to its normal position, bringing the margin-counter-stop 54 forwardly into its operative position. The typing may then proceed in normal fashion to finish the line.

On the rightward return of the carriage to begin a new writing line, the sloping head 41 of the right margin-stop 40 acts as a cam, and enables said stop to pass the counter-stop 54 without again pressing the key 120, as shown in Figures 11 and 12.

It will be understood that the left-hand margin-stop 40 could be similarly rendered impotent to establish the left-hand margin, should it be found desirable to insert typewritten marginal notations.

Any pair of margin-stops on the margin-rack and the corresponding set of stops on the tabulator-rack operate in the same manner with relation to the counter-stop 54, the tabulator-counter-stops 58, etc., the line-end-signal mechanism and the line-end-key-lock mechanism as that described with reference to the margin-stops 40 and the corresponding tabulator-rack-stops.

Variations may be resorted to within the scope 30 of the invention, and portions of the improvements may be used without others.

Having thus described my invention, I claim:

1. In a margin-stop device for a typewriter-carriage, a pair of multi-faced shafts rotatably mounted on said carriage, means synchronizing the rotation of said shafts, margin-stops mounted on one of said shafts for limiting the lateral movement of said carriage, a plurality of intermediate stops adjustably mounted lengthwise of the carriage on the other of said shafts, and means operatively engaging said intermediate stops for determining the intermediate positions of said carriage.

2. In a margin-stop device for a typewriter-carriage, the combination with a pair of multi-faced shafts individually journaled in said carriage, and a mechanism synchronizing the rotation of said shafts, of pairs of margin-stops adjustably mounted on one of said shafts, a counter-stop for operatively engaging said margin-stops for limiting the lateral movement of said carriage, a plurality of intermediate stops adjustably mounted on the other of said shafts, and means operatively engaging said intermediate stops for determining intermediate carriage positions.

3. In a margin-stop device for a typewriter-carriage, the combination with a pair of multi-faced shafts rotatably mounted on said carriage, and gearing synchronizing the rotation of said shafts, of means rotating said shafts into their operative positions, instrumentalities mounted on one of said shafts for limiting the lateral movement of said carriage, a plurality of intermediate stops adjustably mounted on the other of said shafts, locatable in different positions lengthwise of said carriage, and a plurality of counter-stops operatively engaging said intermediate stops for determining intermediate carriage locations.

4. In a typewriting machine having a laterally movable carriage, a pair of multi-faced stop-racks rotatably mounted on said carriage, means synchronizing the rotation of said racks, pairs of margin-stops adjustable lengthwise of said carriage, mounted on one of said racks, a plurality

of intermediate stops adjustably mounted on the other of said racks, a counter-stop operatively engaging said margin-stops for determining the lateral movement of said carriage, instrumentalities operatively engaging said intermediate stops for determining the intermediate locations of said carriage, and means for manually rotating said shafts into their operative positions.

5. In a margin-stop device for a typewriter-carriage, the combination with a pair of multi-faced stop-racks rotatably mounted on said carriage, and means synchronizing the rotation of said racks, of pairs of margin-stops adjustably mounted on one of said racks, a counter-stop 10 interposed between said margin-stops, operatively engaging said stops for determining the lateral movement of said carriage, a plurality of intermediate stops adjustably mounted on the other of said racks, means operatively engaging said intermediate stops for determining the intermediate locations of said carriage, and a knob 15 mounted on one of said shafts for rotating said shafts into their operative positions.

6. In a margin-stop device for a typewriter-carriage, a pair of multi-faced shafts rotatably mounted on said carriage, means synchronizing the rotation of said shafts, a series of equally-spaced indentations in the surfaces of said shafts, margin-stops mounted in the indentations on 20 one of said shafts, a plurality of intermediate stops slidably fitted in said indentations on the other of said shafts, and means operatively engaging said intermediate stops for determining the intermediate locations of said carriage.

35. 7. In a typewriting machine, the combination with a laterally movable carriage, of a pair of multi-faced stop-racks rotatably mounted on said carriage, a pair of margin-stops adjustably mounted in the direction of the carriage travel 40 on one of said stop-racks, counter-stop means therefor to arrest the travel of said carriage so as to establish writing-line limits, a plurality of tabulating stops adjustably mounted on the other of said stop-racks consonant with said margin-stops, and a plurality of tabulating counter-stops 45 interposed between said margin-stops, for additionally arresting said carriage travel intermediate of said margin-stop limits.

8. In a typewriting machine, the combination 50 with a carriage, of a pair of individually rotatable, multi-faced shafts mounted on said carriage, gearing synchronizing the rotation of said shafts, a series of letter-spaced notches cut on the surfaces of said shafts, pairs of margin-stops slidably fitted in said notches on one shaft, counter-stop means therefor, a plurality of intermediate stops slidably fitted in the notches on the other of said shafts, and a plurality of intermediate counter-stops interposed between said intermediate 55 stops for locating the intermediate positions of said carriage.

9. In a typewriting machine, the combination 60 with a carriage, of a pair of multi-faced stop-racks rotatably mounted on said carriage, means synchronizing the rotation of said racks, a margin-control mechanism on one of said racks, a plurality of tabulator-stops adjustably mounted on the other of said racks, a plurality of tabulator-counter-stops interposed between said tabulator-stops, and means selectively placing said tabulator-counter-stops into engagement with 65 said tabulator-stops for determining the intermediate carriage positions.

10. In a typewriting machine, the combination 70 with a carriage, of a pair of multi-faced shafts

rotatably mounted on said carriage, means synchronizing the rotation of said shafts, a series of equally-spaced indentations cut around the periphery of said shafts, pairs of margin-stops 5 slidably fitted in said indentations on one of said shafts, counter-stop means therefor, a plurality of intermediate stops slidably fitted in the indentations on the other of said shafts, a plurality of intermediate counter-stops interposed between said intermediate stops for determining the intermediate 10 positions of said carriage, and means controlling the selection of said counter-stops for engagement with said intermediate stops.

11. In a typewriting machine, the combination 15 with a laterally movable carriage, of a pair of square shafts rotatably mounted in said carriage, means synchronizing the rotation of said shafts, margin-stops mounted on one of said shafts for limiting the lateral movement of said carriage, counter-stop means therefor, a plurality of intermediate stops adjustably mounted upon the other of said shafts, and means operatively engaging 20 said intermediate stops for determining intermediate carriage locations.

12. In a typewriting machine, the combination 25 with a carriage having a pair of square shafts rotatably mounted on said carriage, with means synchronizing the rotation of said shafts, and a series of letter-spaced indentations on the periphery of said shafts, of pairs of margin-stops 30 slidably fitted in the indentations on one of said shafts, a counter-stop operatively engaging said margin-stops for limiting the lateral movement of said carriage, a plurality of intermediate stops slidably fitted in the indentations on the other of said shafts, a plurality of counter-stops operatively 35 engaging said intermediate stops for determining the intermediate locations of said carriage, means rotating said shafts into their operative positions, and means retaining said shafts in one 40 of said operative positions.

13. In a typewriting machine, the combination 45 with a letter-feeding and tabulating carriage, of a plurality of carriage-stop-supporting racks or shafts mounted individually for rotation, one shaft having spaced therearound a plurality of different line-length-defining pairs of margin-stops and the other shaft having a plurality of intermediate or tabulating stops spaced there-around for the different line-lengths, and means 50 coupling said shafts for joint rotation to bring the margin and tabulating stops for any of the different line-lengths to effective position.

14. In a margin and intermediate stop device 55 for a typewriter-carriage, the combination with a pair of shafts rotatably mounted on said carriage, of means synchronizing the rotations of said shafts, pairs of margin-stops, said margin-stop pairs being angularly spaced around and adjustably mounted on one of said shafts, intermediate stops angularly spaced around and adjustably mounted on the other shaft, and counter-stop means co-operative with the margin and intermediate stops, jointly selected by the synchronized rotations of said shafts, for determining 60 the lateral movements of said carriage.

15. In a margin and tabulating stop device for 65 a typewriter-carriage, the combination of a margin and tabulating mechanism including both a margin-stop shaft and a tabulating-stop shaft, 70 said shafts being rotatably mounted individually on said carriage, means synchronizing the individual rotation of said shafts, manipulatable means for rotating said synchronized shafts to different margin and tabulating stop-selecting 75

positions, and a mechanism for retaining said shafts in any of said positions.

16. In a margin and tabulating stop device for a typewriter-carriage, the combination of a margin and tabulating mechanism including both a margin-stop shaft and a tabulating-stop shaft, said shafts being rotatably mounted on said carriage and having the form of racks, means connecting said racks for rotation in concert to different margin and tabulating stop-selecting positions, and a finger-knob connected for rotating said racks to one or another of said positions, said knob having identification symbols, indicating the positions of said racks.

15. 17. In a margin and tabulating stop device for a typewriter-carriage, the combination of a margin and tabulating mechanism including a multi-faced margin shaft and a multi-faced tabulating-stop shaft individually rotatably mounted on said carriage, said shafts being connected for synchronous rotation, each shaft having a series of equally-spaced indentations in the surfaces thereof, margin-stops slidably fitted in said indentations on one of said shafts, tabulating stops in 25 the indentations on the other shaft, and counter-stops for operatively engaging the margin-stops on one shaft and the tabulating stops on the other shaft to determine the lateral movement of said carriage for margin-gaging.

30. 18. In a margin-stop device for a typewriter-carriage, the combination of a pair of stop-racks rotatably mounted individually on said carriage, means connecting said racks for joint rotation, pairs of different line-length-defining margin-stops adjustably mounted on one of said racks, intermediate carriage-stops for the different line-lengths on the other rack, a counter-stop for the margin-stops, and a normally retracted counter-stop for the intermediate stops, the joint rotation 40 of said racks to different line-length-representing positions availing to bring the appropriate margin and intermediate stops jointly into operative relation with said counter-stops.

45. 19. In a typewriting machine having a frame, the combination with a carriage running on said frame, of a pair of stop-racks rotatably mounted on said carriage, means synchronizing the rotation of said racks, a plurality of pairs of margin-stops adjustably mounted on one of said racks for gaging different line-lengths with reference 50 to a certain width and position of a work-sheet, stops on the other rack for stopping the carriage intermediately of the margin-stop places, and counter-stop means on the machine-frame engageable by said margin and intermediate stops, the joint rotation of said racks to different line-length-representing positions availing to bring the appropriate margin and intermediate stops into operative relation with said counter-stop 55 means.

60. 20. In a typewriting machine having a letter-feeding carriage, a pair of square shafts rotatably mounted on said carriage, means synchronizing the rotation of said shafts, a plurality of different line-length-defining pairs of margin-stops adjustably mounted on one of said shafts, interme-

65. diate stops for the different line-lengths adjustably mounted on the other shaft, and counter-stop means operatively engaging said margin-stops and intermediate stops.

21. A stop-mechanism, for a letter-feeding 5 typewriter-carriage, presettable for a predetermined number of independently variable line-lengths and tabulations or indentations therefor, and adjustable for effecting selection of one or another of said line-lengths, including, in combination with said carriage, a plurality of pairs of margin-stops, one pair for each line-length, one or more intermediate stops for positioning the carriage for tabulating or indenting with reference to one or more of said line-lengths, a pair of 10 individually rotatable supporting means on which said margin-stops and intermediate stops are arrayed according to the different line-lengths, each margin-stop and intermediate stop being laterally adjustable individually on said supporting 15 means for individually varying the line-length extents and the tabulations or indentations therefor, counter-stop means, and means enabling said pair of individual supporting means and their arrays of margin and intermediate 20 stops to be adjusted in harmony to one or another line-representing position to bring a corresponding array of said stops into operative relation with said counter-stop means.

22. In a typewriting machine, the combination 30 with a letter-feeding carriage a counter-stop for margin or line-length limiting, and a separate counter-stop for tabulating or line-indenting, of two stop-rack devices, one for different line-length-defining pairs of margin-stops and 35 the other for tabulating or line-indenting stops for the different lines, and means for shifting said two stop-rack devices in unison relatively to said counter-stops for changing from one line-length to another.

40. 23. In a typewriting machine, the combination with a letter-feeding carriage, of a plurality of rotatable members, at least one of said members including a series of line-length-defining stops thereon, one or more of said members also including a series of intermediate stops for line-indenting or tabulating, counterstop means for co-operating with one or another of said stop series, and means controlling the rotative position of said members for removing in harmony any series of stops and replacing in harmony another series of stops, in operative relation with said counterstop means.

45. 24. In a typewriting machine, the combination with a letter-feeding carriage, of different individual arrays of carriage-stops, each array including a rotatable mounting member, certain arrays presenting line-length-defining stops, other arrays presenting intermediate stops for line indenting or tabulating, counterstop means for co-operating with one or another array, and means controlling the rotative positions of said members for removing in harmony any array and replacing it in harmony by any other array, in operative relation with said counterstop means.

50. JESSE A. B. SMITH.
